MACHINE FOR SCALPING METAL WORK
PIECES

Hans T. R. Hanitz, Rockford, Ill., assignor to The
Ingersoll Milling Machine Company, Rockford,
Ill., a corporation of Illinois

Application December 20, 1937, Serial No. 180,759

28 Claims. (Cl. 29—27)

This invention relates generally to the scalping of work pieces such, for example, as elongated bars of metal. In some of its aspects, the invention pertains to the removal of metal 5 from the peripheral surfaces of bars or billets to prepare the same for wire drawing, rolling into sheets, or the like.

One general object of the present invention is to provide a novel machine by which substantially the entire surface of a work blank 10 may be scalped quickly and effectively in the course of a single continuous operation.

A further object is to provide a novel machine in which a metal bar may be straightened and 15 surfaced in a continuous succession of steps so correlated that the straightening pressure is utilized for clamping the bar during at least part of the machining operation.

Still another object is to provide a novel machine tool adapted to straighten successive work blanks and scalp a layer of metal from their entire side surfaces in automatically repeated 20 cycles of operation.

It is another object to provide, in a machine 25 of the above character, a novel arrangement of the cutting tools by which the rough scalped surface may be freed of chip particles or any irregularities.

The invention also resides in various structural characteristics of loading, work clamping and cutter mechanism.

Other objects and advantages of the invention will become apparent from the following detailed description taken in connection with the 35 accompanying drawings, in which:

Figures 1 and 2 are respectively side elevations of the right and left hand portions of a machine tool embodying the present invention.

Fig. 3 is an enlarged fragmentary plan view of 40 the loading end of the machine.

Fig. 4 is an enlarged transverse sectional view along the line 4—4 in Fig. 3.

Fig. 4a is a detail view of a portion of the work transfer mechanism.

Fig. 5 is an enlarged side elevation of the work straightening mechanism.

Fig. 6 is a transverse section taken along the line 6—6 in Fig. 5.

Figs. 7 to 16 are transverse sectional views 50 along the lines 7—7 to 16—16 of Fig. 5.

Fig. 17 is an end elevation of the scalping tool.

Fig. 18 is an enlarged longitudinal sectional view along the line 18—18 in Fig. 17.

Fig. 19 is a fragmentary sectional view taken 55 along the line 19—19 of Fig. 18.

Fig. 20 is an enlarged end elevation partially in section of the work clamping and unloading mechanism.

Fig. 21 is a detailed sectional view along the line 21—21 in Fig. 20.

Fig. 22 is a wiring diagram of the circuits for the motors by which the machine is driven.

Fig. 23 is a schematic view and wiring diagram of the cycle control mechanism.

Fig. 24 is a fragmentary perspective illustration 10 of the cutting action of the scalping tools.

Although the novel machine tool organization herein contemplated is capable of a wide variety of applications, it finds particular utility in the preparation of metal billets for various rolling, 15 drawing, or sheeting operations. Accordingly, the invention is illustrated in the drawings and will be described herein as applied to the scalping of cast bars or billets 20 composed of copper or the like and comprising an elongated cylinder. 20 I do not intend, however, to limit the invention by such disclosure but aim to cover all modifications, alternative structures and methods falling within the spirit and scope of the invention as expressed in the appended claims.

Billets of the character shown have an oxidized peripheral surface which it is desirable to remove in order to prepare the billet for wire drawing, rolling and the like. Also, the bars frequently become bent or distorted during 30 formation or handling, thereby ordinarily necessitating the removal of a thick layer of metal in order to insure complete scalping of the low spots.

The present invention contemplates straightening of the bar to remove all bends and scalping of the entire peripheral surface, all in a continuous automatic operating cycle. In general, the procedure followed involves moving the bar endwise, applying pressure to the bar at 40 spaced points progressing circumferentially around the bar and also longitudinally thereof to straighten the same, scalping of the straightened portion while the trailing portion of the bar is held against turning by the straightening 45 pressure, clamping the leading end against turning while the trailing end is being scalped.

The particular machine shown in the drawings as an illustrative embodiment of the invention includes as its principal elements a work receiving fixture or skidway designated generally by the numeral 21, a straightening mechanism 22, a power driven scalping cutter 23, a power actuated mechanism 24 for feeding the bars 20 endwise into and through the straightening mecha- 50

nism, and a mechanism 25 for pulling the trailing end of the bar through the cutter. All of these mechanisms are carried by an elongated bed 26.

- 5 In the operation of the machine, bars stored in a rack 27 (Fig. 4) are transferred one by one to the skidway 21. Proper positioning of the bar 20 on the skidway 21 actuates a pair of feelers 30 (Fig. 4) which in turn initiates advance 10 of the pusher 24 and feeds the bar endwise through the straightening mechanism 22 and past the scalping tool 23. The portion of bar engaged by the straightening mechanism as the leading end reaches the cutter is gripped so that 15 no separate clamping means is required so long as the bar remains in the straightening mechanism. After the forward end of the bar 20 has been scalped, it is gripped by an automatically actuated clamp device 33 (Fig. 2) embodied in 20 the mechanism 25 and pulled by the latter mechanism until the trailing end of the bar passes the cutter. As soon as the clamp 33 has operated, the pusher 24 is free to return to its starting position to initiate the advance of the next bar. 25 Upon the completion of the scalping, the bar is unclamped and discharged onto a slideway 35 (Fig. 20) for transfer to a suitable conveyor. This cycle is repeated continuously and automatically so that successive bars are automatically straightened and scalped from end to end, each in single continuous operation.

Loading and pusher mechanisms

- 35 A reserve supply of bars 20 is maintained on the storage rack 27 (Fig. 4) preparatory to being operated upon by the machine. The rack shown is of generally rectangular form being made up of longitudinal and transverse bars 36 and 37, respectively, which are joined together as a rigid 40 framework. The inclination of the rack 27 causes the bars 20 to roll to the inner edge of the rack from which the innermost bar is transferred and loaded into the operative position by a mechanism designated generally at 28. 45 The presence of a bar in correct loading position on the rack 27 is detected by a pair of feeler arms 38 pivoted on a bracket 39 which also supports the rack 27. These arms are biased toward the rack by tension springs 40. When a bar 20 50 is rolled against both arms and displaces the same slightly, control switches LS₁ and LS₂ are closed to initiate an operating cycle of the machine. By spacing the feelers along the lower edge of the rack 27 and connecting the switches 55 in series relation, both switches must be simultaneously actuated in order to condition the machine for operation. The machine is thus disabled until a bar to be scalped is properly positioned in longitudinal alinement with the lower edge of the rack.

60 The transfer mechanism 28 for shifting the bars 20 successively from the storage rack to the machine comprises a horizontal rotatable shaft 41 (Figs. 3, 4, and 4^a) having three radially extending annularly spaced arms 43 fast thereon at opposite ends. The shaft 41 is arranged to be driven counter-clockwise as viewed in Fig. 4 by a motor 29 to which the shaft is connected through a worm and worm wheel 44, shaft 45 65 and bevel gears 46. The forward edges or faces of the arms 43 are notched as indicated at 47 to receive the bars, the shaft 41 being so positioned that the arms will rise beneath the lowermost bar only on the storage rack and lift the same upwardly as the shaft rotates. After being ele-

vated to a position above the shaft, the bar carried on the arms 43 rolls out of the notches 47 onto inclined plates 48 along which the bar rolls into the skidway or trough 21. The trough comprises a plurality of the alined generally L-shaped brackets 49 having wear plates 50 thereon. The inclined converging walls of the trough receive the bar 20 and aline it automatically with the opening in the straightening mechanism 22 as well as with the pusher rod 24.

10 Operation of the motor 29 to initiate rotation of the drum 28 to elevate a bar from the rack 37 and transfer the same to the trough 21 is, as above set forth, initiated by joint closure of the bar-detecting switches LS₁ and LS₂. Rotation of 15 the arms 43 is terminated after the bar has been discharged onto the slideway 21, this being effected by a switch LS₄ (Fig. 4^a) actuated by a follower 51 operated by a cam 51^a fast on the shaft 41. The cam has three equally spaced lobes 20 which determine the length of each cycle of the transfer mechanism.

25 In order to insure proper positioning of the bar 20 on the skidway 21 prior to the advance of the pusher 24, an interlock arrangement is provided, 20 which is controlled by the pair of feeler arms 30. As shown in Fig. 3, these arms are generally L-shaped, being pivotally mounted and are biased to a position in which their free ends extend into the space occupied by the bar when correctly 30 positioned on the skidway. In this position of the bar, the feelers are depressed and actuate a pair of control switches LS₅ and LS₁₄ associated with the cycle control mechanism to be described later.

35 The bar advancing mechanism 24 is preferably of the pusher type thus obviating the necessity of clamping the bars. In the construction illustrated, this mechanism includes a push rod or ram 55 supported from one end on a head 52 40 (Fig. 1) slidably mounted on ways 53 on the bed 26. To traverse the head along the ways, a nut (not shown) on the head threads onto a lead screw 54 rotatably supported at opposite ends by the machine bed and driven through suitable speed reduction mechanism 54^a driven by the motor 31. The rod 55, which is of a diameter smaller than the bars 20, butts against the bar 20 positioned in the skidway 21 and pushes the same endwise into and through the straightening mechanism 22 as the head 52 is advanced. 45 Preferably, the motor 31 is controlled so that the pusher head will be advanced at a rapid traverse rate until the leading end of the bar passes the straightener mechanism and approaches the cutter, then at a relatively slower feed rate, and finally is returned to its initial position at a rapid 50 traverse rate.

Straightening mechanism

55 Prior to scalping, each of the bars 20 is straightened so as to remove any kinks or bends and thereby enable a minimum thickness of metal to be removed while at the same time insuring scalping of the entire cylindrical surface of the bar. For this purpose, the bars are preferably advanced endwise past a series of abutments positioned to progressively flex the bars laterally in several directions out of and then back into a true rectilinear path. In the present instance, the bar is bent laterally in six different directions by abutments in the form of positively positioned rollers disposed at spaced points along the path of the bar and spaced progressively around the bar. The side of each roller which engages the bar as it passes is positioned to shift 60

the bar laterally from the center line along which it enters and leaves the straightening mechanism. The kinks thus formed in the bar are removed by spring pressed guide rollers and a final set of alining rollers. All of the rollers are mounted within a casing 56 (Fig. 5) in the form of a hollow casting rigidly supported on the bed 26.

A bar 20 entering the straightening mechanism 22 is first engaged by a set of three equally spaced 10 guide rollers 57 (Fig. 6) which serve to aline the bar properly. These rollers are journaled in yokes 58 to turn about axes extending transversely of the bar axis. The yokes are slidable radially in bore 62 and are urged toward the bar by 15 heavy compression springs 59 surrounding studs 60 on the yokes. The springs act against cup-shaped caps 61 threaded in the bores 62. Lock nuts 63 serve as means of adjusting tension in the springs 59 and also act to limit the inward 20 movement of the rollers when the latter are not in engagement with a bar. Keys 64 prevent rotation of the yokes but allow axial movement. It will be noted that peripheries of the rollers 57 are grooved to conform generally with the 25 contour of the bars 20, this same shape being also used in all of the guide and straightening rollers.

After passing through the guide rollers 57, the bar next engages a straightening roller 65 (Fig. 7) journaled in a yoke 66. This yoke has a fixed 30 rather than yieldable mounting being carried by a stud 67 held in position by a lock nut 68. This mounting permits, however, adjustment for the yoke 66 and roller 65 toward and away from the bar 20 so that the amount of lateral flexure of the 35 bar caused by its contact with the straightening roller 65 can be varied. This adjustment also facilitates arrangement of the mechanism for receiving bars of different diameters. Other straightening rollers 69 to 73 inclusive shown in 40 Figs. 8, 10, 11, 13, and 14 are all provided with a supporting structure substantially like that described for roller 65 above. Preferably, the straightening rollers are grouped in pairs, each 45 pair including two rollers disposed for contact with the bar at diametrically opposed points, although all of the rollers are arranged in spaced relation longitudinally of the bar. Thus, the roller 69 is diametrically opposite to the preceding straightening roller 65. Similarly, the fixed 50 rollers are arranged in pairs 70-71 and 72-73 and positioned to flex the bar in opposite directions along diameters which are spaced sixty degrees in opposite directions from the diameter along which the bar is flexed by the rollers 65 and 69. By virtue of this longitudinal and 55 angular spacing of the rollers 65 and 69 to 73, the bar in passing the rollers will be flexed in six different directions and thus caused to travel in a sinuous path by which it is straightened effectively.

Yieldably supported guide rollers disposed between the adjacent pairs of bending rollers operate to remove the kinks in the bar produced by the latter rollers without the necessity of placing 65 the leading end portion under tension. Thus, as is shown in Fig. 9, a pair of guide rollers 74 is arranged to receive the bar after it leaves the straightening rollers 65 and 69. An adjustable and yieldable mounting for these guide rollers is provided which is substantially identical with that heretofore described for the guide rollers 57. It will be noted that the guide rollers 74 contact the bar along substantially the same diameter as the straightening rollers 65, 69. A similar pair 70 of yieldably mounted guide rollers 75 (Fig. 12),

arranged to contact the bar on the same diameter as the straightening rollers 70-71, receives the bar after it passes through the latter rollers.

A final set of three positively positioned straightening rollers 76 (Fig. 15) arranged at intervals 5 of 120 degrees about the periphery of the bar, contact the bar simultaneously after it has passed the previous flexing abutments or rollers 72, 73. Upon leaving this last set of fixed rollers, the bar 20 passes through a set of guide rollers 77 (Fig. 16) arranged substantially identically with the entrance guide rollers 57 (Fig. 6). These two groups of rollers positively aline the bar with the axis of the scalping tool and maintain the leading end of the bar in position for properly entering 15 the cutter.

The progressive flexing or kinking of the bars from end to end alternately in opposite directions and progressively around the bar followed by unkinking or straightening of the bends serves 20 to thoroughly straighten each longitudinal element of the bar. In addition, the pressure applied by the straightening and guide rollers is utilized to hold the bars against rotation so that the forward or straightened end of the same 25 may be scalped as it emerges from the straightening mechanism. This not only eliminates the necessity of providing any other clamping mechanism for preventing rotation of the bar during 30 scalping but also reduces to a minimum the overall length of the machine.

Scalping cutter

Since the bar leaving the straightening mechanism has a substantially perfect cylindrical surface, the scale or oxide on the entire periphery may be eliminated by removing only a very small layer of metal. This is accomplished by the scalping mechanism 23 which is arranged to scalp the cylindrical periphery of the bar by cutting a series of helical ribbons therefrom as 35 illustrated in Figs. 17 and 24.

The cutter proper comprises a rotary body 81 encircling the bar being scalped and carrying a series, three in the present instance, of radially disposed blades 80 fastened in elongated holes 81^a in the body as by screws 82 (Figs. 17 and 18). The blades project into a central opening 83 in the body and have edges 80^a which enter the periphery of the bar to the proper depth and cut 40 chips 80^b (Fig. 24) of widths determined by the rate at which the bar is fed axially. The blade face 80^c along which the chips follow from the point of formation at the cutting edge is of 45 concave curvature and shaped as shown to lead the chips outwardly and away from the cutter body. In this way, the chips are removed effectually from the cutting zone and fall free of the work. Any fine particles of the removed metal which 50 fall from the blades are caught in dished recesses 55 in the face of the body 81^d and by centrifugal force are thrown out through holes 81^e.

To remove any irregularities left by the roughing blades 80, an auxiliary blade 83^a is mounted in the body in the same manner as the blades 80 and preferably is disposed between two of the latter blades. The edge 83^b extends along the periphery of the bar so as to take a light shaving cut and remove a metal layer which is very thin in a radial direction and substantially wider than 70 the chips 80^b cut by the roughing blades. Any irregularities left by the blades 80 are thus removed leaving a smooth finished surface free from any metal particles. The chips removed by the shaving tool follow along curved surface 83^c.

and are disposed of in the same way as the chips 80^b.

The cutter body 81 is fastened by screws 81^c to the end of a rotatable pulley or sleeve 84 (Fig. 18) having grooves 85 formed in the outer surface thereof for the reception of V-belts 86 by means of which the sleeve is driven by a suitable driving motor 87 (Fig. 2). The pulley 84 is journaled on a cylindrical extension 88 projecting from a bracket 89 on the bed 26. Herein the pulley bearing includes a liner 90 fast within the pulley and rotatable with an apertured sleeve 91 interposed between it and cylindrical support 88. Lubricant is supplied under pressure through a conduit 92 from a suitable motor driven pump 92^a (Fig. 2) and after flowing through a passage 93 (Fig. 18) in the supporting member 88, passes through branch passages 94 registering with the apertures in the sleeve 91, thereafter flowing between the contacting surfaces of the bearing sleeves 91 and 88. Lubricating oil then returns to a suitable sump through an oil return passage 95 cored out of the bracket 89. Provision is thus made for lubricating the cutter bearing effectively.

The cutter is rotated at a relatively high speed, and consequently it is desirable that some means be provided for supporting or steadyng the end of the bar 20 beyond the cutter. For this purpose, a series of guide rollers 96 (Figs. 18 and 19) are positioned within the supporting member 88. As best shown in Fig. 19, three such guide rollers are provided at intervals of 120 degrees about the periphery of the bar. Each roller is journaled on a pin in the forked end of a supporting arm 97 extending longitudinally of the member 88 and pivotally fulcrumed intermediate its ends on a pin 99 supported by lugs 99^a. The outer ends of the arms are tapered as indicated at 100 and are positioned between the complementary tapered inner end portions of two threaded sleeves 101 and 102. The sleeve 101 is threaded into the central bore in the member 88 while the sleeve 102 is threaded into the sleeve 101. By adjusting the sleeves, the arms 97 may be tilted about their pivots 99 to move the guide rollers 96 toward and away from the bars 20. In this way, the rollers may be set to accommodate bars of different sizes.

Puller and unloading mechanisms

When the leading end of the bar 20 has been advanced through the cutter and to a predetermined position beyond the cutter mounting, this end is gripped by the clamp 33 on the traversing mechanism 25 so that the remainder of the bar may be pulled through the cutter to effect scalping of the trailing end of the bar. During a short interval of time, the pushing and pulling mechanisms 24 and 25 cooperate in advancing the bar being scalped, movements of the two being synchronized during this interval. The puller mechanism comprises in general the clamp 33 mounted on a carriage 103 (Fig. 2) which is reciprocated along ways 104 on the bed 26 by a lead screw 105 driven by the electric motor 34 and threading into a nut on the head.

Since the puller head is driven by an independent drive motor, provision is made for starting this motor and allowing the head to attain substantial synchronism with the pusher head before the clamp 33 becomes effective. Accordingly, the puller head motor is started in response to movement of the leading end of the bar past

the cutter and movement of this head is utilized to initiate actuation of the clamp 33.

The clamp (Fig. 20) comprises a pair of cooperating jaws 106 and 107 slidable along ways 107^a on the carriage 103 and oppositely threaded so as to mate with the right and left hand threaded sections of the screw 108. When the screw shaft 108 is rotated in one direction, the jaws are moved bodily toward each other into engagement with the bar interposed therebetween. During reverse rotation, both jaws are moved simultaneously out of clamping engagement. The screw shaft 108 is journaled in a bracket 109 secured to the forward end of the pusher head 103. The driving motor 33^a for the clamp is connected to the shaft 108 by means of a belt 110 passing over a pulley 111 which in turn drives a worm 112 meshing with a worm wheel 113 fast on the end of the screw shaft.

In order to shut off the clamping motor automatically at the termination of the clamping operation, a switching mechanism has been provided which is arranged for actuation in response to a predetermined clamping pressure on the jaws 106, 107. Two switches LS₁₂ and LS_{12a} are secured to the bracket 109 and arranged to be actuated by a pivoted arm 114 (Fig. 20). This arm is in turn disposed to be moved by a pin 115 (Fig. 21) slidably mounted within a bore 116 fashioned in the bracket 109 and biased into engagement with the projecting end of the worm 112 by a compression spring 117. The latter acts between a shoulder 118 on the pin 115 and a retaining cap 119 threaded in the end of the bore 116. The adjacent end of the worm 112 is journaled in a suitable bearing 120 provided in the inner end of the pin 115 so that in effect a floating mounting is provided for the worm. It will thus be seen that when the jaws 106, 107 are firmly clamped against one of the bars 20, the worm 112 is locked against further movement and continued rotation of the worm 112 will cause the worm to move axially. This compresses the spring 117 and moves the pin 115 axially outward to shift the switch actuating arm 114.

Upon further reference to Fig. 20, it will be also seen that a second pair of switches LS₁₁ and LS_{11a} are included in the clamping head mechanism 33. These switches are arranged to be actuated by a pivoted arm 121 which is in turn moved in response to engagement with an adjustable stop 121^a upon endwise movement of the clamp 106. As is hereinafter described, the switch LS_{11a} is arranged to stop the unclamping operation of the motor 33^a while the switch LS₁₁ initiates the return of the puller head 103 when the unclamping operation is completed.

As the bars 20 are released by the clamp 33, they roll downwardly along a skid plate 35^a onto any suitable conveyor (not shown). This plate is in the present instance supported on the puller carriage 103.

Electric control devices

In order that the machine may be entirely automatic in operation, a control arrangement has been provided embodying a plurality of switches arranged to be actuated in response to various positions or movements of the work piece and cooperating elements of the machine tool. In addition to the switches previously mentioned, the cycle is controlled by a series of switches operated in response to certain positions of the pusher and puller heads 52 and 103 respectively.

Referring to Fig. 1, a series of dogs are pro-

vided on the pusher head 52 arranged to actuate various switches secured to the side of the bed 26. For example, a dog 121 serves to actuate switches LS₃ and LS_{3a} which respectively condition a circuit for starting the loading motor 29 and open a shunt circuit to enable the skid feeler switches LS₅ and LS₁₄ to initiate a cycle if a bar is in correct loading position. Similarly, the dogs 122 actuate a two position switch LS₁₃ for changing the rate of movement of the pusher head 52 from a rapid traverse rate to a feed rate and for resetting the same while dogs 123 and 124 actuate switches LS₇ and LS₈ respectively to start the puller drive motor 34 and to stop the pusher motor 31.

In somewhat the same manner, the puller head 103 is provided with a dog 125 arranged to actuate switches LS₆ and LS_{6a} for stopping the puller head motor 34 and initiating the unclamping movement for the unloading operation. Also, dog 126 on the puller head actuates a switch LS₁₀ to initiate a rapid return movement of the puller head 103 after the bar has been moved completely through the cutter 23 while dog 127 actuates a switch LS₈ connected in the control circuit of the puller head motor 34.

A series of manually operated switches are provided for general supervisory and safety control of the machine tool. These switches may be conveniently grouped on a panel 128 (Fig. 2) and include a normally open starting push button switch S₁ (Fig. 22) for the tool head driving motor as well as an associated stop switch S₂ and an emergency stop switch S₃. It will be noted that the switches S₂ and S₃ are connected in series relation, thus in general performing the same function. The emergency stop switch S₃ may, however, be located at some point on the machine remote from the panel 128 so as to be readily available to the operator. A cycle starting switch S₄ (Fig. 23) serves to initiate the operation of the machine in its automatic cycle after the tool driving motor has been started, and a switch S₅ serves to stop the automatic cycle. Switches S₆ and S₇ are effective respectively to condition the control circuits for an automatic return of the pusher head 52 and of the puller head 103. Finally a manually operated two-position switch S₈ conditions the control circuit for stoppage of the machine at the end of the cycle through which it is operating at the time the switch is actuated and this switch must be manually reset in order for the machine to recycle.

The various driving motors and elements of the machine tool are controlled from the automatic and manually operated switches through a series of control relays R₁ to R₂₅. The various contacts of these relays have been designated with the letters RC and a subscript for the R indicating the relay number and a subscript for the C indicating the particular set of contacts. Thus the relay R₁, for example, has two sets of contacts R₁C₁ and R₁C₂.

In order to simplify the illustration of the wiring connections the energizing circuits for the various driving motors have been shown in Fig. 22 together with their cooperating relays. Only the contacts of these relays which are interposed directly in the motor circuits have been included in Fig. 22, however. The remaining relay contacts are shown with their associated relays in Fig. 23 which also includes the control and energizing circuits for the relays.

Current is supplied to the various driving motors from supply lines L₁L₂ as shown in Fig. 22.

These same supply lines also furnish current to the relay and control circuits (Fig. 23). It will be noted upon reference to Fig. 22, however, that the motor starting switch S₁ must be closed before any current is supplied to the automatic cycle control circuits illustrated in Fig. 23, thus affording an effective safety interlock which prevents the advance of a work blank into the cutter when the latter is not rotating.

Automatic cycle of operation

The electrical control arrangement embodied in the machine tool described is adapted to effect a continuously repeated operation of the machine through an automatic cycle including the steps 15 of:

- (1) Transfer of a bar 20 from the storage rack 27 to the skidway 21;
- (2) Rapid approach of the pusher head 52 to engage the bar on the skidway by the ram 55 20 and advance the same to the straightening mechanism;
- (3) Relatively slower feed of the pusher 55 while the forward portion of the bar 20 is being advanced through the cutter; 25
- (4) Initiation of the feeding movement of the puller head 103 in the direction of movement of the advancing bar and in synchronism with the pusher head;
- (5) Actuation of the clamping mechanism 33 30 into engagement with the scalped forward end of the bar;
- (6) Rapid return of the pusher 55 to starting position when the leading end of the bar has been gripped by the puller; 35
- (7) Rapid advance of the puller head after the bar has been completely scalped;
- (8) Stoppage of the puller head 103;
- (9) Unclamping of the scalped bar and discharge thereof from the machine; 40
- (10) Rapid return of the puller head 103.

From the foregoing, it will be seen that the pusher head 52 returns to starting position to initiate the advance of another bar before the puller head 103 has released the preceding bar. 45 By this means, the operating speed of the machine is increased and the bars or work blanks are advanced through the machine in rapid succession despite their substantial lengths.

Motor circuits

Upon reference to Fig. 22, it will be seen that the loading or transfer mechanism driving motor 29 as well as the tool head driving motor 37 have each been illustrated as being of the compound type, the motor 29 having an armature 129, a series field 130 and a shunt field 131, while the motor 37 has an armature 132, a series field 133 and a shunt field 134. A manually adjustable rheostat 135 serves to vary the shunt field excitation of the motor 37 and consequently its speed. The clamping motor 33a is reversible being provided with an armature 136, a series field 137 and shunt field 138. Connection of this motor for rotation in one direction or the other is effected by means of two sets of associated reversing relays R₁₉—R₂₀ and R₂₁—R₂₂. The pusher and puller motors 31 and 34 are also reversible, motor 31 being provided with an armature 139, a series field 140 and a shunt field 141 while the motor 34 is 70 provided with an armature 142, a series field 143, and a shunt field 144.

Rapid traverse movement of the heads associated with the motors 31 and 34 is effected through the medium of rapid traverse relays R₁₃

and R_{18} respectively which serve to vary the resistance of the circuits of the field windings 141 and 143 by shunting resistors 145 and 146 while cutting resistors 147 and 148 into circuit.

In order to obtain synchronous operation of the pusher and puller head driving motors 31 and 34, manually adjustable rheostats or resistors 149 and 150, are connected in their field circuits. These calibrating resistors may be varied in order to obtain equal speeds for the motors. In some cases, however, it is desirable to vary the speeds of the two driving motors 31 and 34 simultaneously as, for example, when different size work blanks are being machined and for this purpose the rheostats 145 and 146 are connected in tandem, that is, actuated in the same sense by a common manually operable adjusting mechanism 151 (mounted on the bed 26 adjacent the panel 128 as indicated in Fig. 2) so that the speeds of the two motors may be varied simultaneously by like amounts.

Two sets of reversing relays are associated with each of the head driving motors 31 and 34. Thus, the relays R_9-R_{10} and $R_{11}-R_{12}$ serve to connect the motor 31 for opposite directions of rotation. Similarly, the relays $R_{14}-R_{15}$ and $R_{16}-R_{17}$ are alternatively available for connecting the motor 34 for opposite directions of rotation.

The tool driving motor 81 is started and the control circuits rendered operable for cyclic operation of the machine by momentary closure of the drive starting switch S_1 thereby energizing the self sealing relay R_{25} (through a circuit $L_1-S_1-152-R_{25}-153-S_3-S_2-154-L_2$) which thus closes its contacts $R_{25}C_1$ to form a sealing circuit therefor through the conductor 155 in shunt with switch L_1 as well as to complete a circuit to the remainder of the supply line S_1 , while closure of the other set of contacts $R_{25}C_2$ completes a circuit for the driving motor 81 ($L_1-R_{25}C_2-156-157-132-133-L_2$), the shunt field 134 being connected across the armature by conductors 158, 159 and rheostat 135.

The transfer mechanism driving motor 29 is energized upon actuation of its associated relay R_8 . Closure of the relay contacts R_8C_1 connects the armature 129 and series field 130 (through a circuit $L_1-R_8C_1-160-129-130-L_2$) as well as the shunt field 131 (through a circuit $L_1-R_8C_1-161-131-L_2$).

In order to effect a clamping movement of the jaws 106-107 (Fig. 20) the clamping motor 33^a is energized for rotation in the corresponding direction by actuation of its associated relays $R_{20}-R_{19}$ (Fig. 22). Thus, upon closure of these latter relays, the motor is energized for operation in one direction (through a circuit $L_1-162-163-R_{20}C_1-136-164-R_{19}C_1-165-137-L_2$) and similarly actuation of relays $R_{21}-R_{22}$ connects the motor for rotation in the opposite direction to effect an unclamping movement of the jaws (through a circuit $L_1-162-R_{22}C_1-164-136-R_{21}C_1-165-137-L_2$). The shunt field 138 is connected at all times across the supply lines L_1-L_2 by a conductor 162.

The motor 31 is energized to advance the pusher head 52 by energization of the associated relays $R_{11}-R_{12}$. Upon closure of these relays, the motor is energized for an advancing feed movement (through a circuit $L_1-166-167-R_{11}C_1-168-139-169-R_{12}C_1-170-140-L_2$) while closure of the other associated set of relays R_9-R_{11} energizes the motor for rotation in the opposite direction (through a circuit $L_1-166-171-R_9C_1-169-139-168-R_{10}C_1-170-140-L_2$). The shunt

field 141 is connected in circuit between the supply lines L_1-L_2 at all times. As was previously noted, the degree of energization of this field and consequently the speed of the motor is determined by a rapid traverse relay controlled shunt connections 172 and 173 as well as the settings of the adjustable rheostats 149 and 145.

The supply circuits for the puller head motor 34 are substantially identical with those described above with respect to motor 31. Thus, energization of the associated relays $R_{14}-R_{15}$ connects the motor for rotation in a direction to move the puller head 103 away from the straightening mechanism (through a circuit $L_1-174-175-R_{15}C_1-176-142-177-R_{14}C_1-178-144-L_2$) while energization of a second set of relays $R_{16}-R_{17}$ connects the motor 34 for rotation in the opposite direction (through a circuit

$L_1-174-175-179-R_{17}C_1-171-142-R_{16}C_1-178-144-L_2$).
20

As in the case of the motor 31, the shunt field 143 for the motor 34 is also connected at all times between the supply lines L_1-L_2 and its degree of energization is controlled by the associated rapid traverse relay R_{18} and the setting of the manually adjustable rheostats 150 and 146.
25

Cycle control circuits

Automatic cyclic operation of the machine is initiated by momentary closure of the cycle starting switch S_4 . Various interlocking relays are associated in the circuit in such manner that a bar 20 must be properly positioned on the storage rack 27 preparatory to being transferred to the machine and further the pusher head 52 must be in its fully retracted position before the cycle of operation can be initiated under the control of the switch S_4 . Closure of this switch S_4 momentarily energizes the relay R_1 (through $L_1-180-S_4-181-R_1-L_2$) whose closure energizes a self-sealing relay R_2 (through a circuit $L_1-180-S_5-182-R_1C_2-183-R_2-L_2$) and a second self-sealing relay R_3 (through a circuit

$L_1-184-S_8-185-LS_2-LS_1-186-R_1C_1-187-R_3-L_2$).
45

The relay R_2 is maintained closed after the momentary closure of relay R_1 by its sealing contacts R_2C_1 in shunt with the contacts R_1C_2 , and similarly the relay R_3 is maintained closed by its sealing contacts R_3C_1 arranged in shunt with the contacts R_1C_1 . It will be noted that the energizing circuit for the relay R_3 includes the feeler actuated switches LS_1 and LS_2 so that this relay cannot be closed unless a bar is in position on the lower edge of the storage rack 27 ready for transfer to the machine. In the event that no bar is there to close these feeler switches, the relay R_3 will remain open and the cycle starting switch S_4 must be momentarily closed again after a bar has been properly positioned on the rack. The relay R_3 is one of the two relays which must be closed in order to effect energization of the transfer motor control relay R_8 . The second of these supervisory control relays is R_5 which is normally energized when the pusher head 52 is in its fully retracted position (through a circuit $L_1-188-LS_3-189-R_{10}C_2-190-R_5-L_2$), the inclusion of the switch LS_3 in the energizing circuit of this relay serving to insure that the pusher head will be in its fully retracted position before the machine can be started. As a further safety precaution, contacts $R_{10}C_2$ are included in the circuit of the relay R_5 so that the transfer motor 75

29 cannot be inadvertently started at any time when the motor 31 of the head 52 is energized by closure of its relays R₉R₁₀. With the relays R₃ and R₅ closed, the relay R₈ is energized (through a circuit L₁—R₂C₂—191—192—R₃C₁—193—R₃C₂—194—R₇C₁—195—R₈—L₂) to start the transfer motor 29.

Closure of the relay R₈ as described above, in response to a momentary closure of the cycle starting switch S₄, energizes the transfer motor 29 as heretofore described and causes one of the bars 20 to be shifted from the storage rack 27 to the skidway 21 in the first step of the cycle of operation. As soon as the transfer motor 29 starts, the cam 51 is moved to close the switch LS₄ so that in general the control of the transfer motor 29 is shifted to the relay R₆ which is cam controlled and will be opened to stop the motor after the transfer arms 43 have rotated through an arc of 120 degrees. Thus, closure of the switch LS₄ energizes the relay R₆ (through a circuit L₁—196—197—LS₄—198—R₆—L₂) thereby closing its contacts R₆C₁ and R₆C₂ which respectively energize the relay R₇ (through a circuit L₁—196—R₆C₂—R₆C₁—R₇—L₂) and place a shunt about the now opened contacts R₇C₁ in the energizing circuit of the transfer motor relay R₈ (through a circuit 199—R₈C₂—200). The inclusion of the contacts R₆C₂ in the circuit of relay R₇ prevents operation of the transfer motor 29 except when the pusher head 52 is in its initial position. After the motor 29 has executed its cycle and consequently shifted the bar to the skidway 21, the switch LS₄ is again opened, thereby deenergizing relay R₆ which in turn deenergizes the relay R₈ to stop the motor 29.

The second step in the cycle of operation, namely, a rapid advance of the pusher head 52, is initiated by the positioning of a bar in the skidway 21 to close the feeler actuated switches LS₆ and LS₁₄. Closure of these switches LS₆ and LS₁₄ energizes control relays R₁₁ and R₁₂ for the pusher head driving motor 31 (through a circuit

L₁—R₂C₂—191—201—S₆—202—203—LS₁₄—LS₅—204—LS₈—205—R₁₀C₃—206—R₁₁—R₁₂—L₂)

which in turn start the motor 31. Inclusion of the interlock contacts R₁₉C₃ in the circuit for the relays R₁₁—R₁₂ prevents inadvertent simultaneous actuation of the two sets of relays R₉—R₁₀ and R₁₁—R₁₂. Energization of the relay R₁₂ also energizes the rapid traverse relay R₁₃ (through a circuit L₁—R₂C₂—191—207—LS₁₃—208—R₁₂C₂—R₁₃—L₂) which changes the field excitation of the driving motor 31 to cause the same to move at a rapid traverse rate. As the head 52 moves away from its initial position, switch LS₃ is opened and LS_{3a} closed thereby deenergizing the relay R₅ and energizing relay R₄ respectively. Cutting out R₅ prevents inadvertent actuation of the transfer mechanism motor 29 until the pusher head has again been restored to its starting position while closure of the relay R₄ prepares a part of the circuit used in effecting the return movement of the pusher head. Also its contacts R₄C₂ complete a shunt about the skidway feeler switches LS₅—LS₁₄ to permit movement of head 52 after they open while its contacts R₄C₃ retain R₃ energized.

The third step in the cycle of operation, namely, advance of the head 52 at a relatively slow feed rate, is initiated by opening of the switch LS₁₃ which is effected by the dog 122 as the leading end of the bar approaches the cutter. This breaks the circuit of the rapid traverse relay

R₁₃ causing it to open thereby decreasing the speed of the motor 31 to a lower feed rate.

Initiation of the feeding movement of the puller head 103 in the fourth step of the cycle of operation occurs as the pusher head 52 approaches the straightening mechanism. In this movement, a dog 123 on the head 52 closes the switch LS₇ which completes a circuit for the relays R₁₄ and R₁₅ (through a circuit L₁—R₂C₂—191—209—S₇—210—LS₉—211—R₂C₁—212—LS₇—213—214—R₁₄—R₁₅—L₂). When energized, these relays connect the motor 34 to move the puller head 103 to the left (as viewed in Fig. 23) in synchronism with the pusher head 52. As soon as the puller head 103 starts, the switch LS₆ is closed thereby energizing relay R₂₄ (through a circuit L₁—227—LS₆—226—R₂₄—L₂) so that the contacts R₂₄C₃ shunt out the momentarily closed switch LS₇ and retain R₁₄ and R₁₅ energized. Energization of relay R₁₅ also serves to initiate operation of the clamping mechanism 33. Thus, upon closure of its contacts R₁₅C₂, a circuit is completed for relays R₁₉ and R₂₀ of the clamp driving motor 33^a (through L₁—R₂C₂—191—215—LS₁₂—216—R₁₅C₂—217—R₁₈—R₂₀—L₂). The clamping motor 33^a thus started moves the jaws 106—107 into clamping engagement with the leading end of the advancing bar. When the clamping is completed, the switch LS₁₂ is opened thereby deenergizing the relays R₁₉ and R₂₀ and stopping the motor. At the same time, switch LS_{12a} is closed to initiate the sixth step in the cycle of operation, namely, rapid return of the pusher head 52 to its initial position.

In the course of the clamping operation, the pusher head 52 continues its advancing movement whereupon the switch LS₈ is opened and the switch LS_{8a} closed by the dog 123. These switch operations serve respectively to stop the pusher head and prepare a circuit for effecting return movement of the head after the clamping operation is completed. Thus, opening of the switch LS₈ interrupts the energizing circuits for the relays R₁₁ and R₁₂ to stop the motor 31. Closure of switch LS_{12a} upon the completion of the clamping operation combined with closure of the switch LS_{8a} complete a circuit for effecting a rapid return movement of the pusher head 52. Thus the return relays R₉ and R₁₀ are energized when the two switches LS_{12a} and LS_{8a} are closed (through a circuit

L₁—R₂C₂—191—215—LS_{12a}—218—LS_{8a}—219—220—R₄C₁—221—R₉—R₁₀—L₂).

It will be noted that the relay R₄ was previously energized (through a circuit

L₁—188—LS_{3a}—222—R₄—L₂)

upon closure of the switch LS_{3a} as the pusher head started its advancing movement so that the contacts R₄C₁ were previously closed for the circuit just described of the return relays R₉ and R₁₀. The pusher head 52 returns at a rapid return rate since the rapid traverse relay R₁₃ is energized by closure of the relay R₁₀ (through a circuit L₁—223—R₁₀C₄—R₁₃—L₂). The pusher head 52 continues its return movement resetting the switch LS₁₃ and finally closing the switch LS₃ and opening the switch LS_{3a}. Opening of the latter switch deenergizes the relay R₄ thereby also dropping out the relays R₉ and R₁₀ and stopping the motor 31. Closure of the switch LS₃ again completes the circuit for relay R₈ so that the first step in the cycle of operation of the machine will be initiated immediately if another

bar is in loading position on the storage rack. In the event that no bar is present, the relay R_3 will be deenergized by the opening of the feeler switches LS_1 and LS_2 and relay R_4 .

- 5 After the bar carried by the clamping mechanism 33 has been machined from end to end, the speed of the puller head 103 is increased to a rapid traverse rate. This is initiated by closure of the switch LS_{10} actuated by a cooperating dog 126 on the puller head which energizes the rapid traverse relay R_{18} (through a circuit

$L_1-R_2C_2-191-224-LS_{10}-225-226-R_{18}-L_2$).

The eighth step in the cycle of operation, namely, stopping of the puller head 103 in its limit position, is effected by opening of the switch LS_6 by the dog 125. The energizing circuit for the puller head motor relays R_{14} and R_{15} is thus interrupted so that these relays are deenergized 20 and the motor consequently stopped. At the same time, the cooperating switch LS_{9a} is closed preparatory to the unclamping operation.

Unclamping of the bar occurs in the ninth step of the cycle and is controlled through the medium of relays R_{23} and R_{24} . As was previously noted, the latter relay R_{24} is energized when the switch LS_6 is closed by the dog 125 as the head 103 starts to advance, the circuit being through $L_1-227-LS_6-226-R_{24}-L_2$. The associated contacts $R_{24}C_1$ interposed in the energizing circuit of the relay R_{23} are thus closed. The energizing circuit for this latter relay is completed (through

$L_1-229-LS_{9a}-230-231-R_{24}C_1-R_{23}-L_2$)

35 when the puller head reaches its fully retracted position as evidenced by closure of the switch LS_{9a} by the dog 125. Relay R_{23} together with the switch LS_{11a} previously closed during the clamping operation complete an energizing circuit for relays R_{21} and R_{22} of the clamp actuating motor 33^a to cause it to move the clamping jaws to unclamped position. Thus, the relays R_{21} and R_{22} are energized upon closure of relay R_{23} (through a circuit

45 $L_1-232-LS_{11a}-233-R_{23}C_2-234-R_{21}-R_{22}-L_2$)

Since the relay R_{23} remains energized during this unclamping operation and subsequent return of the head 103, its associated contacts $R_{23}C_1$ are 50 retained opened so that there is no danger of inadvertent reclosure of the motor control relays R_{14} and R_{15} even when the switch LS_9 recloses on the return of the head.

Completion of the unclamping operation 55 closes the switch LS_{11} to start the return movement of the puller head 103 to its original position. The switch LS_{11a} is opened to thereby de-energize the relays R_{21} and R_{22} and stop the clamping motor while the simultaneous closure 60 of the switch LS_{11} completes a circuit for the puller head return relays R_{16} and R_{17} (through

$L_1-232-LS_{11}-235-R_{24}C_2-R_{23}C_3-236-R_{16}-R_{17}-L_2$)

65 Energization of the relay R_{17} also closes its contacts $R_{17}C_2$ to thereby energize the associated rapid traverse relay R_{18} (through a circuit $L_1-227-R_{17}C_2-226-R_{18}-L_2$). As the puller head 103 starts its return movement, the switch LS_9 is 70 again closed and the switch LS_{9a} opened. This does not deenergize the relay R_{23} since it is retained closed by its sealing contacts $R_{23}C_4$. Upon the return of the puller head to its initial position, however, the switch LS_9 is opened thereby 75 interrupting the energizing circuit of the relay

R_{24} which in turn deenergizes the relay R_{23} thereby stopping the puller head driving motor by de-energizing its return relays R_{16} and R_{17} . The switch LS_{10} is reset during the return movement of the puller head so that on the final opening of the switch LS_6 the circuits are all returned to their initial or starting condition preparatory to a repetition of the cycle. 5

The machine may be stopped at any time in the course of its automatic cycle of operation by 10 opening a stop switch S_5 to thereby deenergize the master control switch or relay R_2 . It will be noted from the circuits previously described that contacts R_2C_2 of the master relay R_2 are interposed directly in the energizing circuits of the 15 transfer motor relay R_8 , pusher head motor relays R_{11} and R_{12} , puller head motor relays R_{14} and R_{15} , rapid traverse relays R_{13} and R_{18} , and clamp actuating motor relays R_{19} and R_{20} so that as a result, the opening of the master relay R_2 will 20 cause a complete stoppage of all of the associated driving motors, namely, the transfer motor 29, the clamp mechanism motor 33^a, the pusher head motor 31, and the puller head motor 34 during the advance of the bar. On the other hand, the return relays R_9 and R_{10} for the pusher head motor, the rapid traverse relay R_{13} , when the pusher head is returning, the pulley head relays R_{16} and R_{17} , the traverse relay R_{18} , the unclamping relays 25 R_{21} and R_{22} and their associated control relays R_{23} and R_{24} are all connected directly to L_1 . Thus, the return movements of all the movable elements may be completed as long as the drive motor 87 is running.

After the machine has been stopped at any desired point during the advance of the bar, the pusher head 52 may be returned to its initial position by actuating the return switch S_6 . This switch serves to complete an energizing circuit for the pusher head return relays R_9 and R_{10} independently of the master relay R_2 (through a circuit $L_1-231-S_6-238-220-R_{4}C_1-221-R_9-R_{10}-L_2$). It will thus be seen that upon actuation of the return switch S_6 , the motor 31 is energized to return the pusher head 52 to its initial 40 position at a rapid traverse rate, the rapid traverse rate relay R_{13} being closed by the relay R_{10} as previously described. Similarly, actuation of the return switch S_7 serves to effect a rapid return movement of the puller head 103 to its initial position. Actuation of the switch S_7 from its normal position shown in Fig. 23 energizes the relay R_{23} (through a circuit $L_1-229-239-S_7-240-231-R_{24}C_1-R_{23}-L_2$). Energization of this relay completes the circuit to the relays R_{16} and R_{17} as previously described. It will be noted that the switch S_8 is provided with a pair of normally closed contacts interposed in the energizing circuits for the relays R_{11} and R_{12} while the switch S_7 is provided with a similar pair of contacts interposed in the energizing circuits for the relays R_{14} and R_{15} . Consequently, inadvertent actuation of these latter sets of relays is prevented during the time that the switches S_8 and S_7 are used to effect a return movement of the associated heads. 55

In the event that it is desired to stop the machine at the end of any particular cycle through which it happens to be operating, the switch S_8 is opened. From Fig. 23, it will be seen that this switch is interposed in series relation with the feeler controlled switches LS_1 and LS_2 and serves to stop the machine in much the same manner as do these feeler switches in the event that either one of them is opened due to the lack of a rough 70 75

bar on the storage rack 27. Thus, when the pusher head 52 returns to its initial position preparatory to beginning a new cycle of operation, if the switch S₈ is open, the relay R₃ will drop out as soon as the relay R₄ is deenergized and consequently, the transfer motor 29 will not be started, or in other words, the next cycle will not be initiated.

As was previously noted, the machine may also be stopped at will by opening either of the switches S₂ or S₃ (Fig. 22) which serve to deenergize the main control switch or relay R₂. Opening of the relay contacts R₂₅C₁ not only open-circuits all of the driving motors 29, 31, 33, 15 and 34, but also deenergizes all of the control relays R₁ to R₄ inclusive so that the machine is instantly rendered inoperative.

I claim as my invention:

1. A machine tool for scalping round bar-shaped blanks comprising, in combination, means supporting the bar for endwise movement, means including a plurality of abutments disposed at spaced points along the path of the bar in its endwise movement for flexing the same laterally in a plurality of directions and progressively from end to end whereby to straighten the same, a first bar advancing means for pushing the bar endwise past said abutments in operative engagement therewith, means including a power rotated scalping tool for removing a helical layer of metal from the advancing bar as it leaves said abutments, the pressure exerted on the bar by said abutments serving to hold the bar against rotation, and a second bar advancing means for pulling said bar after a portion thereof has been scalped, said second bar advancing means including a clamping mechanism engageable with the scalped leading end portion of the bar.

2. A machine tool for scalping a cylindrical bar comprising, in combination, means supporting the bar for endwise movement, means including a plurality of abutments disposed at spaced points axially of the path of the bar in its endwise movement for flexing the same laterally in a plurality of directions and progressively from end to end whereby to straighten the bar, a means for pushing the bar past said abutments in operative engagement therewith, and means including a power rotated scalping tool for removing a layer of metal from the advancing bar as it leaves said abutments, the pressure exerted on the bar by said abutments serving to hold the bar against rotation.

3. In a machine for scalping elongated cylindrical bars, the combination of a metal-removing tool for scalping the surface of a bar advanced past the same, a power actuated work advancing mechanism located on one side of said tool for pushing the elongated bar endwise into operative relation with said tool, a second power actuated work advancing mechanism located on the opposite side of said tool and engageable with the machined portion of the blank leaving said tool for pulling the remainder of the blank past said tool whereby the blank may be effectively scalped through its entire length during a single endwise movement thereof past said tool, and means including a plurality of guide rollers contacting said bar adjacent said tool for not only guiding said bar but also frictionally holding the same against rotation.

4. In a machine for scalping elongated work blanks, the combination of a metal removing tool for scalping the surface of a work blank advanced past the same, a power actuated mech-

anism located on one side of said tool for advancing the elongated work blank endwise into operative engagement with said tool, a second independently actuated work advancing mechanism located on the opposite side of said tool and engageable with the machined portion of the blank leaving said tool for pulling the remainder of the blank past said tool whereby the blank may be effectively scalped through its entire length during a single endwise movement thereof past said tool, and control means for maintaining said first and second work advancing mechanisms in substantial synchronism while they are both in operative relation with a common work blank.

5. In a machine for scalping elongated work blanks, the combination of a metal removing tool for scalping the surface of a work blank, a power actuated work advancing mechanism located on one side of said tool for pushing the work blank endwise into operative engagement with the tool, a second power actuated work advancing mechanism located on the opposite side of said tool and engageable with the machined portion of the blank for pulling the remainder of the blank past said tool whereby the blank may be effectively scalped through its entire length during a single pass along the tool, and means rendered operative in response to engagement of the blank by said second work advancing mechanism to return said first work advancing mechanism to its initial position for engagement with another work blank.

6. In a machine for scalping elongated work blanks, the combination of a metal removing tool, a power actuated mechanism located on one side of said tool for advancing the elongated work blank endwise into operative relation with said tool, a second power actuated work advancing mechanism located on the opposite side of said tool and operable to clamp the machined end portion of the blank and pull the remainder of the blank past said tool whereby the blank may be effectively scalped through its entire length during a single pass along said tool, first control means for initiating movement of said second work advancing mechanism in response to the advance of the work blank to a predetermined position, a second control means for causing a return movement of said first work advancing mechanism to its initial position, and means for maintaining said work advancing mechanisms in substantial synchronism during the interval between the actuations of said first and second control means.

7. In a machine for scalping cylindrical bars, the combination of an elongated horizontal bed, a tool support mounted on an intermediate portion of said bed for rotation about a horizontal axis extending longitudinally of the bed, power actuated means for rotating said tool support, means including a scalping tool carried by said support for removing a helical surface layer of metal from a bar advanced longitudinally past said tool, means for supporting a bar for endwise movement along said bed past said tool, means including a ram movable along said bed to advance the bar along said supporting means by pushing contact with only the butt end surface of the work piece, a clamping device engageable with the scalped portion of the bar, and power actuated means for traversing said clamping device along said bed away from said tool to complete the advance of the bar.

8. In a machine for scalping cylindrical bars,

the combination of an elongated horizontal bed, a hollow drum mounted on an intermediate portion of said bed for rotation about a horizontal axis extending longitudinally of the bed, power actuated means for rotating said drum, means including a scalping tool carried by said drum and projecting into the interior thereof for removing a helical surface layer of metal from a bar advanced longitudinally through said drum, 10 means for supporting a bar for endwise movement along said bed through said drum, means including a ram movable along said bed for pushing the bar along said supporting means to advance the leading portion thereof through said 15 drum, a clamping device engageable with the scalped leading end of the bar, power actuated means for traversing said clamping device along said bed away from said drum to complete the advance of the bar past said scalping tool, means 20 for synchronizing the movements of said ram and said clamping mechanism while in engagement with a common work piece, and means operating as an incident to completion of the clamping operation of said device for retracting 25 said ram.

9. In a machine tool organization, the combination of a metal removing tool, means for pushing a work piece endwise toward and into engagement with said tool, and automatically operating mechanism for gripping the leading portion of the work piece beyond said tool and pulling the trailing portion thereof past the tool.

10. A machine tool having, in combination, a metal removing tool for scalping the surface of a work piece, a work advancing mechanism located on one side of said tool for moving the work piece into operative engagement with said tool and advancing a portion of the work piece past said tool at a relatively slow feed rate, a 40 clamping mechanism located on the opposite side of said tool and disposed for engagement with the scalped portion of the work piece, power actuated means for moving said clamping mechanism toward and away from said tool, means 45 responsive to movement of the leading end of the work piece into a predetermined position in its path of advance for initiating operation of said clamping mechanism and movement thereof away from said tool at said relatively slow feed 50 rate in synchronism with said work advancing mechanism, and means responsive to the movement of the work piece out of engagement with respect to said tool for stopping said clamping mechanism, disengaging the same from the work 55 piece and initiating operation of said power actuated means to return said clamping mechanism to its initial position at a relatively fast rapid return rate.

11. In a machine tool of the character set forth, the combination of a metal removing tool for scalping the surface of a work blank advanced past the same, a work advancing mechanism located on one side of said tool for pushing an elongated work blank endwise into operative relation with said tool, a traversable clamping mechanism located on the opposite side of said tool and engageable with the machined portion of the blank leaving said tool for pulling the remainder of the blank past said tool, first power 65 actuated means for traversing said work advancing mechanism toward said tool at a relatively slow feed rate, a second power actuated means for traversing said clamping mechanism toward and away from said tool, means responsive to movement of the blank past said tool to initiate op-

eration of said second power actuated means to move said clamping mechanism away from said tool in substantial synchronism with said work advancing mechanism at a relatively slow feed rate, means responsive to the initial movement 5 of said clamping mechanism at said feed rate for actuating the same to clamp the machined end of the work blank, and means responsive to effective clamping of said blank for initiating return of said work advancing mechanism to its 10 initial position.

12. In a machine tool of the character described, the combination of a metal removing tool for scalping a work blank advanced past the same, a work advancing mechanism located on one side of said tool for moving a work blank 15 into operative engagement with said tool and advancing a portion of the blank past said tool at a relatively slow feed rate, a clamping mechanism located on the opposite side of said tool 20 and disposed for engagement with the scalped portion of the blank leaving the tool, power actuated means for moving said clamping mechanism toward and away from said tool, and means responsive to engagement of the blank by said 25 clamping mechanism for interrupting the advance of said work advancing mechanism and for returning the same to its initial position.

13. A machine tool having, in combination, a surfacing tool, a power actuated pusher for feeding an elongated work piece toward and partially past said tool, a power actuated clamp on the side of said tool opposite said pusher, power actuated mechanism operable in response to movement of the leading end portion of the work piece past 30 said tool to initiate advance of said clamp away from the tool at a speed substantially equal to that of said pusher, means responsive to the advance of said clamp to initiate operation of the clamp to grip said leading end portion, means 35 operable as an incident to clamping of the work piece to cause rapid return of said pusher, means responsive to movement of the trailing end portion of said work piece past said tool to release said clamp, and means operable upon complete 40 unclamping of the work piece to rapid return 45 the clamp for engagement with a succeeding work piece.

14. A machine tool having, in combination, a surfacing tool, a power actuated pusher for feeding an elongated work piece toward and partially past said tool, a power actuated clamp on the opposite side of said tool, a separate power actuated mechanism for moving said clamp, means operable in response to movement of the leading end portion of the work piece past said 50 tool to initiate gripping of the work by the clamp and advance of said clamp away from the tool at a speed substantially equal to that of said pusher, means operable as an incident to clamping 55 of the work piece to initiate rapid return of said pusher, and means responsive to movement of the trailing end portion of said work piece past said tool to release said clamp and initiate rapid return thereof.

15. A machine tool having, in combination, a surfacing tool, power actuated means for feeding an elongated work piece toward and past said tool, a power actuated clamping mechanism, power actuated mechanism for moving the clamp 70 longitudinally of the work path, means operable in response to movement of at least a portion of the work piece past said tool to initiate operation of said mechanisms to clamp the work piece and advance the clamp away from the tool,

- means operable as an incident to clamping of the work piece to interrupt the operation of said feeding means, means responsive to movement of the work piece past said tool to a predetermined unloading position to release said clamping mechanism and return the same for engagement with a succeeding work piece.
16. In a machine tool organization, the combination of a metal removing tool for operating on the surface of an elongated work blank passed by the same, a clamping mechanism located in the path of the work blank as it leaves said tool, means responsive to the movement of the blank for actuating said clamping mechanism to grip a machined portion of the blank, and power actuated means for traversing said mechanism away from said tool after clamping of the blank.
17. In a machine tool organization, the combination of a pair of opposed clamping jaws adapted to receive a work piece therebetween, power actuated means for effecting relative clamping movement between the jaws to grip a work piece, means including a worm and worm wheel forming a driving connection between said power actuated means and at least one of said jaws, means yieldably supporting said worm for endwise movement, and means responsive to a bodily endwise displacement of said form for rendering said power actuated means inoperative to increase the clamping pressure on said jaws.
18. A machine tool having, in combination, a rack adapted to support a plurality of elongated work pieces side by side, means for operating upon a work piece moved into engagement therewith, mechanism for advancing successive work pieces to said operating means including a pusher engageable with one end of a work piece disposed in alignment therewith, a skid adapted to position a work piece discharged thereon in alignment with said pusher, and a transfer mechanism for shifting work pieces successively from said rack to said skid.
19. A machine tool having, in combination, a rack adapted to support a plurality of elongated work pieces side by side, means for operating upon a work piece moved into engagement therewith, mechanism for advancing successive work pieces to said operating means including a pusher engageable with one end of a work piece disposed in alignment therewith, a skid adapted to position a work piece discharged thereon in alignment with said pusher, and means responsive to the return of said pusher to its initial position for initiating the next actuation of said transfer mechanism.
20. A machine tool having, in combination, a rack adapted to support a plurality of elongated work pieces side by side, means for operating upon a work piece moved into engagement therewith, mechanism for advancing successive work pieces to said operating means, a slideway adapted to position a work piece discharged thereon in alignment with said mechanism, and power operated mechanism for elevating the work pieces one by one from said rack and discharging the same onto said slideway.
21. A machine tool having, in combination, a rack adapted to support a plurality of elongated work pieces side by side, means for operating upon a work piece moved into engagement therewith, mechanism for advancing successive work pieces to said operating means including a pusher engageable with one end of a work piece disposed in alignment therewith, a support adapted to
- position a work piece discharged thereon in alignment with said pusher, a power actuated transfer mechanism for shifting work pieces one by one from said rack to said support, and means controlled jointly by the return of said pusher to starting position and the presence of a work piece in loading position in said rack to initiate operation of said transfer mechanism.
22. A machine tool having, in combination, a rack adapted to support a plurality of elongated work pieces side by side, means for operating upon a work piece moved into engagement therewith, mechanism for advancing successive bars to said operating means including a power actuated pusher engageable with one end of a work piece disposed in alignment therewith, a support adapted to position a work piece discharged thereon in alignment with said pusher, a power driven rotatable carrier operable in a partial revolution to elevate a work piece off from said rack and deliver the same to said support, means for detecting proper positioning of a work piece on said rack for initiating operation of said carrier, and means controlled by the presence of a work piece in proper position on said support to initiate advance of said pusher.
23. A machine tool having, in combination, means for operating upon an elongated work piece during endwise movement thereof, a pusher engageable with one end of the work piece for advancing the same to said operating means, a skid tending to position a work piece discharged thereon in alignment with said pusher, a plurality of feelers engageable with a work piece at spaced points along said skid and operable to detect correct positioning of a work piece thereon, and power actuated mechanism controlled by the joint action of said feelers for initiating the advance of said pusher.
24. In a machine tool, the combination of a tool support, a work support adapted to receive an elongated work piece, power actuated means for feeding the work piece along the work support to the tool on the tool support, a plurality of spaced feelers actuatable by the work piece when positioned correctly on said work support, and means responsive only to an actuation of all of said feelers for rendering said power actuated means operative.
25. In a scalping machine, the combination of a rotatably mounted hollow cutter body, means supporting a bar work piece for endwise movement through said body, a metal removing tool carried by said body for scalping metal from the surface of a bar passed through the body, power actuated means for rotating said body about its longitudinal axis, and means providing an opening in said body extending in a generally radial direction from the interior thereof and forming a passage through which metal chips cut from the surface of the bar are discharged by centrifugal action.
26. In a scalping machine, the combination of a power rotated cutter body having a central opening, means for feeding a cylindrical work piece axially through said opening, and a plurality of annularly spaced tools on said body projecting into said opening and having cutting edges adapted to remove helical metal ribbons from the work piece fed through the body, said blades having concave faces shaped to induce a flow of the chips outwardly from the work piece and also longitudinally of the latter in a direction reverse to the movement thereof.
27. In a scalping machine, the combination of

10 a power rotated cutter body having a central opening, means for feeding a cylindrical work piece axially through said opening, a plurality of annularly spaced tools on said body projecting into said opening and having cutting edges adapted to remove helical metal ribbons from the work piece fed through the body, and a separate blade carried by said body and having a cutting edge positioned to remove from the scalped surface a layer of metal substantially thinner in a radial direction and wider in a longitudinal direction than the ribbons cut by said first mentioned edges.

28 A machine tool having, in combination, a surfacing tool, a work advancing mechanism operable upon successive work pieces to advance the leading end portions thereof past said tool, a reciprocable puller operable to grip each work piece at a point spaced beyond said tool, a power actuated mechanism adapted when started to execute an automatic cycle during which said puller is first moved away from said tool and then back to starting position, and means controlled by the movement of each work piece to initiate a cycle of operation of said mechanism.

HANS T. R. HANITZ.
